UNITED STATES PATENT OFFICE

GEORGE I. GOLDWYN, OF CHICAGO, ILLINOIS

BAG

Application filed March 31, 1930. Serial No. 440,200.

This invention relates to improvements in bags and it consists of the matters herein-after described and more particularly pointed out in the appended claims.

5 The bag with which my invention is concerned is of the type made from a piece of bag material such as burlap, folded over upon itself to provide the two walls of the bag, the marginal parts of one end and the sides of 10 which are then stitched together, thus leaving the bag open at one end.

The primary object of the invention is to provide an improved manner of securing marginal parts of associated bag walls together as a seam, which seam is strong and durable in service and is neat in appearance.

A further object of the invention is to provide an improved seam for the bag which is practical to make and which eliminates 20 the necessity of turning the bag inside out during the making thereof.

Still another object of the invention is to provide a bag seam wherein marginal parts of the bag walls are each folded to provide 25 a plurality of thicknesses that are turned back upon the bag walls and are secured to said walls in a manner eliminating any frayed or raveled edges.

These objects of the invention as well as 30 others together with the many advantages thereof will more fully appear as I proceed with my specification.

In the drawing:—

35 Fig. 1 is a perspective view of a bag embodying my invention.

Fig. 2 is a sectional view on an enlarged scale through a partially completed bag seam embodying one form of my invention.

40 Fig. 3 is a sectional perspective view showing the finished seam after certain further operations have been carried out on the partially finished seam of Fig. 2.

Fig. 4 is a view similar to Fig. 3 showing another seam structure embodying my invention.

45 Fig. 5 is a detail sectional view through a seam embodying a further modified form of the invention.

50 Referring now in detail to that embodiment of the invention illustrated in Figs. 1

to 3 inclusive, 1 indicates as a whole a textile bag such as burlap having side walls 2 and 3 respectively which are secured together along the bottom end and along one side thereof to leave an open mouth at the other end thereof. In accordance with one embodiment of the invention, the lateral margin 2^a and 3^a respectively of each bag wall is turned over upon the outer surface of the associated wall and a line of stitching 4 is then run along said margins to secure the bag walls and turned over margins 2^a and 3^a respectively together. Thereafter the free edge portion 2^b and 3^b respectively of each marginal part which is usually more or less frayed or raveled is turned over in a reverse direction upon the other portion of said part so as to enclose or cover the line of stitching 4. Thereafter a line of overcast stitching 5 is run in just within the folded over portions of the bag walls with the transverse loops 6 of the same passing about said folded over margins to bind in place all ravelings at the edges of both portions 2^b and 3^b respectively of said marginal parts.

In burlap bags which are always more or less loosely woven, the edges of said marginal portions are generally frayed or raveled and said edges tend to slough off as lint in the use of the bag, when such edges are exposed and this is not only objectionable as a matter of untidy appearance but is also objectionable because there the bag quickly wears away. However, in my improved bag 80 the edges of said portions of said marginal parts are bound in place so that they cannot slough off as lint and a much neater appearance is given to the bag as a whole.

85 In this respect it is pointed out that the invention may be used in the remade bag industry because when a burlap bag such as is now used is turned inside out it presents a seam such as is shown in Fig. 2. I take such a bag and turn over the free edge portions 2^b and 3^b respectively of the marginal parts 2^a and 3^a and then run the stitching 5 as before mentioned and the remade bag is thus provided with a much stronger and neater 90 seam than it had before.

In making new bags, I may if desired eliminate the stitching 4 before mentioned and so locate the line of stitching 5^a that it passes through not only both bag walls 2 and 3 but 5 also through both the edge portions 2^b and 3^b adjacent the line of fold with the margins 2^a—3^a, the loops 6^a passing about the outer edge portions of the seam as before so as to bind the frayed or raveled edges of the portions 2^b and 3^b in place as before. Such an 10 arrangement is best shown in Fig. 4.

In Fig. 5 I have shown a modified form of construction somewhat similar to that shown in Fig. 3 the only difference being that instead of turning the portions 2^b and 3^b back 15 over upon the portions 2^a and 3^a I turn said portions 2^b and 3^b back under said portions 2^a and 3^a respectively. Thus when a line of stitching 5^b is run in, the loops 6^b enclose 20 the edges as before and the frayed or raveled edges of the portions 2^b and 3^b are more effectively protected and concealed.

It is apparent that a bag embodying my 25 invention is provided with a good strong and neat appearing seam which can be readily produced at a low labor and material cost.

While in describing my invention, I have referred in detail to the form and arrangement of the parts thereof, the same is to be 30 considered merely as illustrative so that I do not wish to be limited thereto except as may be specifically set forth in the appended claims.

I claim as my invention:—

35 1. A bag having side walls, a marginal part of each of which is folded to provide a plurality of thicknesses turned back upon the outside of associated side walls, and means securing said side walls together as well as 40 securing said marginal parts thereto and to each other, said means including parts that pass about the folds of said margins and provide a bound edge for the bag.

2. A bag having side walls, a marginal 45 part of each of which is folded to provide a plurality of zigzag thicknesses turned back upon the outside of associated side walls, and stitching passing through said side walls as well as binding said thicknesses in place 50 and to said side walls of the bag.

3. A bag having side walls, a marginal 55 part of each of which is folded over in one direction upon the outside of an associated side wall, a portion of said marginal part being refolded in the other direction and engaged under the first mentioned portion of said marginal parts and stitching securing said side walls together as well as securing said marginal parts together and to said side 60 walls, a portion of said stitching passing about the folds of said margins and providing a bound edge for the bag.

In testimony whereof, I have hereunto set my hand, this 28th day of March, 1930.

65 GEORGE I. GOLDWYN.
